DESIGN FOR A TAX CALCULATOR

Arthur A. Golub, Malverne, and Zoltan Hartmann, Baldwin, N. Y.

Application September 22, 1943, Serial No. 111,190

Term of patent 3½ years

(Cl. D52—1)

To all whom it may concern:

Be it known that we, Arthur A. Golub and Zoltan Hartmann, citizens of the United States, and residing, respectively, in Malverne, county of Nassau, and State of New York, and in Baldwin, county of Nassau, and State of New York, have invented a new, original, and ornamental Design for a Tax Calculator, of which the following is a specification, reference being had to the accompanying drawing, forming part thereof.

Fig. 1 is a front elevational view of a tax calculator, showing our new design.

Fig. 2 is a rear elevational view; and

Fig. 3 is an edge elevational view thereof.

We claim:

The ornamental design for a tax calculator, substantially as shown.

ARTHUR A. GOLUB.
ZOLTAN HARTMANN.
